(57) **CLAIM**

The ornamental design for a wedge for weightlifting, as shown and described.

DESCRIPTION

FIG. 1 is a top, front, right perspective view of a wedge for weightlifting showing my new design;

FIG. 2 is a bottom, rear, right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent to the shaded areas define the bounds of the claimed design and form no part thereof. The broken lines depicting the remainder of the article form no part of the claimed design.
